PELICAN HOOK

William Robert MacCluney, Brooklyn, N. Y.

Application November 25, 1943, Serial No. 511,728

5 Claims. (Cl. 294—83)

1

This invention relates to a releasable hook of the type commonly referred to as a pelican hook, designed especially for marine work, although it will obviously be of utility wherever a hook is required capable of withstanding great strain and of being releasable while under strain. Such hooks ordinarily comprise a pair of links pivoted together, foldable into a position where they constitute a hook and retainable in that folded position by a restraining link which nevertheless can be lifted to a nonrestraining position.

It is an object of this invention to provide a hook of the character described which will withstand large stresses in proportion to its dimensions without yielding, but which nevertheless may be readily opened.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description, taken in connection with the accompanying drawing, in which:

Fig. 1 is a side elevation of a hook embodying this invention in the closed position.

Fig. 2 is a view taken from the other side showing the hook in open position with the restraining link raised.

Fig. 3 is a front elevation of the hook in the closed position.

In the drawing the numeral 10 designates generally an elongated link, one end of which, as at 11, serves as a pivot for a link 12, one end of the link 12 having a bearing opening 13 at one end to surround the pivot end 11 for that purpose. The link 12 is bent outwardly and then upwardly, as shown at 14, to furnish adjacent to the pivot 11 an eye portion 15. Its upper end 16 is arranged to nest within an upper portion of the link 10.

Each side of the link 10 is provided with a lug or extension 17 on one side thereof, and in these lugs 17 there is pivoted a link 18. This link is arranged to swing downwardly to engage the upper end 16 of the link 12 or to swing upwardly to free that upper end. This upper end 16 of the link 12 at a point where it engages the lower end 19 of the link 18 is curved, as shown at 20, substantially along a radius centered about the center of the pivot 21 of the link 18, so that strain tending to move the link 12 will not tend to slip the link 18 upwardly to release the link 12. In

actual practice the curve 20 is slightly undercut sufficiently to tend to hold the link 18 in place, but not sufficiently to offer too great an obstruction to the deliberate raising of the link 18 when it is desired to release the hook.

In order still further to reduce the tendency of the hook to open under strain, the pivot center 21 and the point of contact between the curved surface 20 and the link 18 are approximately in alignment with the eye portion 15.

It would be understood that any strain imposed upon the eye portion tends to pull downwardly upon the link 12, while at the same time, because of the pivot 11, it tends to swing end 19 to the right, as shown at Fig. 1. The sum of the forces produces a strain which is not quite in alignment with pivot 21 and the link 19. For this reason the link 18 will therefore also preferably not be in exact alignment with the eye 15.

To facilitate opening of the hook, the link 18 may be provided with a projecting stem 25 integral therewith, and a handle 26 has at each end a bearing 27 by which it is pivoted to the stem. With this construction it will be clear that when the hook is in closed position, the handle member 26 may be swung about the stem 25 into the position shown in Fig. 3, and shown in dotted lines in Fig. 1, where it lies beside the link 12. A spring catch 28 is carried upon the handle 26 in position to engage and latch upon the underside of the link 12, thus accomplishing the double function of holding the handle in place and of offering very considerable resistance against any raising of the link 18 by jar or accident, or by bending of the parts under excessive strain.

The curved portion 20 which, as we have stated, is substantially concentric about the pivot center 21, may be continued for any length desired, and in many cases it may be continued to the end of the link. For some purposes, however, I prefer to provide an additional recess 30 between the curved portion 20 and the end of the link, so that in the event any jar might momentarily raise the link 18, it would nevertheless be caught within the recess 30 and restrain the opening of the hook. This recess 30 has the further advantage that the hook may be held in partially closed position during adjustment of the parts to which it is to be connected by placing the lower end 19 of link 18 in this recess 30 while making adjustment of the connecting part, and then when these adjustments are made, the end 19 may be slipped down over the projection 20 and forced into place closing the toggle.

55 A link 31 is preferably provided at the top of

the link 10 for convenience of attachment to a cable or chain or the like.

These hooks are frequently used under conditions where the strain is at times momentarily relaxed, and under such circumstances there is sometimes a tendency for the pivoted link 12 to swing inwardly, and then when the strain is again applied, to move outwardly with increased force. To avoid the possibility that the link 12 might under such circumstances strike the link 18 and throw it upwardly, improperly releasing the hook, I prefer to provide upon the link 20, upon the inside of the pivot 21, a lug 32 in position to engage the backside 33 of the end 16 of link 12, this lug being so positioned that as the link 18 is swung downwardly to lock the link 12 in place, the lug 32 will come into engagement with the backside 33 and preferably will slip slightly over dead center, thereby holding the link 12 rigidly against vibration in either direction.

I also prefer to provide upon the side of the link a lug 40 in position and of a size to permit the link 18 to snap over it as the link is brought to the position shown in Fig. 1, and to hold the link 18 resiliently against being thrown upwardly by accident.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A hook of the character described comprising a main link having an attaching means at one end and a second link pivoted to its other end, said second link being curved outwardly from its pivot to form an eye and having its upper end nested within said main link when in closed position, a retaining link pivoted to said main link in position to be swung over the free end of the curved link to engage the same, or upwardly above the free end to release the same, and a lug upon said main link in position to cause the retaining link resiliently to engage it as the retaining link is swung into retaining position and to bear against the retaining link to hold it in retaining position.

2. A hook of the character described comprising a main link having an attaching means at one end and a second link pivoted to its other end, said second link being curved outwardly from its pivot to form an eye and having its upper end nested within said main link when in closed position, a retaining link pivoted to said main link in position to be swung over the free end of the curved link to engage the outer side of the same, or upwardly above the free end to release the same, and a lug upon said retaining

link in position to press against the side of the free end of the curved link opposite to the said outer side, whereby the said free end is retained against movement in either direction.

3. A hook of the character described comprising a main link having an attaching means at one end and a second link pivoted to its other end, said second link being curved outwardly from its pivot to form an eye and having its upper end nested within said main link when in closed position, a retaining link pivoted to said main link in position to be swung over the free end of the curved link to engage the same, or upwardly above the free end to release the same, and a lug upon said main link in position to cause the retaining link resiliently to engage it as the retaining link is swung into retaining position and to bear against the retaining link to hold it in retaining position, and a second lug upon said retaining link in position to press against the side of the free end of the curved link opposite to the said curved surface, whereby the said free end is retained against movement in either direction.

20 4. A hook of the character described comprising a main link having an attaching means at one end and a second link pivoted to its other end, said second link being curved outwardly from its pivot to form an eye and having its upper end nested within said main link when in closed position, a retaining link pivoted to said main link in position to be swung over the free end of the curved link to engage the same, or upwardly above the free end to release the same, 25 30 said free end having a curved surface at the point where it engages said retaining link, the curvature being such that the retaining link is urged downwardly by pressure against such surface, said surface terminating at its upper end in a recess constructed and arranged to receive the lower end of said retaining link when it slips above said surface.

40 45 5. A pelican hook comprising a main link having at one end a chain receiving portion, a movable arm pivoted to the other end of said link having a pair of recesses in its free end and a closing mechanism pivoted to said main link constructed to engage one of said recesses to hold said link partly closed and the other of said recesses to hold said link completely closed.
